RAIL SUPPORT AND FASTENING MEANS

Application filed October 13, 1930. Serial No. 488,237.

This invention relates to an improved rail support and fastening means, and has particular reference to an arrangement of tie plates, means for anchoring a rail to the tie plates, and means for anchoring the tie plates to the ties.

The main objects of the invention are to provide an improved method of securing a rail to a tie wherein a tie plate is utilized and whereby the plate is firmly secured to the tie so as to practically eliminate mechanical wear or destruction of tie fibre; to provide an arrangement in which the normal vertical or wave movement of the rail is permitted to occur without withdrawing or loosening the spikes used to secure the tie plates to the tie; to provide a tie plate and rail-anchoring arrangement in which clips are secured to the tie plate on opposite sides of the rail for securing the latter to the tie plate, and in which the same type of clips may be utilized interchangeably on both sides of the rail; to provide an arrangement including double shoulder tie plates and clips which facilitates the use of lower shoulders on the tie plate than has heretofore been practicable; to provide an arrangement in which the tie plates are free from spike-holes in the zone of greatest stress, i. e., under the edges of the rail base flange or under the rail-abutting shoulders; to provide an arrangement whereby looseness of the tie-plate-fastening means incident to embedment of the tie plate in the tie is automatically taken up; to provide a rail-anchoring clip structure which facilitates positioning or removal of the clip, especially in connection with the use of screw spikes; to provide a clip structure which facilitates withdrawal of the fastening spikes when driven or cut spikes are used; to provide an arrangement in which certain of the clips are welded to the tie plates to obtain an additional safety factor, while at the same time permitting removal or replacement of the tie plates without requiring removal of the welded-on clip from the tie plate.

Other objects and advantages of the invention will be understood by reference to the following specification and accompanying

drawings (two sheets), in which the invention is illustrated in certain selected embodiments.

In the drawings:

Fig. 1 is a cross section through a rail immediately in front of the tie and the rail-supporting-and-fastening means carried by the tie;

Fig. 2 is a plan of the structure shown in Fig. 1;

Fig. 3 is a plan similar to Fig. 2, but on a reduced scale, and illustrating a modified arrangement;

Fig. 4 is a view similar to Fig. 1, but illustrating a modified structure;

Fig. 5 is a top plan of the arrangement shown in Fig. 4;

Fig. 6 is a fragmentary section on the line 6—6 of Fig. 4, and

Fig. 7 is a plan illustrating an improved track mounting embodying certain of the features of the invention.

Referring now to Figures 1 and 2 of the drawings, I have illustrated the lower portion of a rail in cross section at 10, the rail including a base flange which extends laterally on opposite sides of the web part in accordance with conventional rail construction. The rail 10 is positioned on a wood or other suitable tie 11, a tie plate 12 being interposed between the bottom of the rail and the tie.

The tie plate 12 is illustrated, in this instance, as being of that type which embodies a pair of rail-abutting shoulders 13 and 14 which are disposed at the opposite sides of the rail seat portion 15 of the tie plate. Projecting outwardly from the opposite sides of the rail seat portion and outwardly beyond the shoulders 13 and 14 are tie plate end portions 16 and 17. The standard practice of practically all railroads in the United States is to require the rail to be canted slightly inwardly, and hence the surface of the intermediate or rail seat portion 15 is disposed at the desired angle to the horizontal, substantially as illustrated. The bottom surface of the tie is disposed in a substantially horizontal plane and is adapted to be seated on the tie 11, which is, of course, seated in the road-

bed so that its top surface is substantially horizontally disposed.

For anchoring the rail to the tie plate, I provide fastening clips 23 on opposite sides 5 of the rail, the clips on opposite sides being of like construction and shape. In order to accommodate the same type of clip on either side of the rail, the upper surfaces of the opposite end portions of the tie plate are made 10 substantially alike so that the clips are interchangeably mountable on either side of the rail. The top surface portions of the respective tie plate end portions on which the clips are seated may be referred to as clip seats 15 and these seats may be specially formed surface portions, or, as in this case, they may consist merely of portions of the respective top surfaces which are of substantially uniform configuration across the entire width of the 20 plate. As shown in Figure 1, each clip includes a main body portion 24 and an upwardly offset lip portion 25 which projects from one end of the body portion into overlying relation to the adjacent portion of the 25 rail base flange. As shown, the overlying lip portion is spaced vertically from the rail flange so as to permit free limited movement of the rail in a vertical direction as an incident to its normal wave motion under passing 30 train loads. Each clip includes a shoulder portion 26 which constitutes in effect a vertical extension of the respective rail-abutting shoulders of the tie plate. Hence, it will be seen that the rail-abutting shoulders 35 13 and 14 may be made somewhat lower than the standard practice has heretofore required, with the consequent saving in weight of the tie plate.

The main body portion of each clip 23 is 40 provided with a spike-receiving aperture 27 disposed substantially centrally of said body portion, i. e., spaced inwardly a material distance from the edges of the clip body, the rear or outer end of said body being provided with a notch communicating with said aperture, as clearly shown in Figure 2. Headed screw spikes, such as indicated at 28, may be passed through the openings 27 in the clips and through suitable openings 29 45 which are punched in the tie plate, and into the tie 11 for securing the clips to the tie plate and the tie plate to the tie. The provision of the open-sided spike-receiving apertures in the clip body permits the clip to be 50 inserted under a partially driven spike or removed from under a spike which is only slightly backed out of the tie. An advantage in saving of time necessary for removing the clip is thus obtained and tie fibre is subjected 55 to less mechanical wear incident to renewal and replacement of the clip and spike. The clips may be reinforced by means of ribs, such as indicated at 30, extending lengthwise 60 at the opposite sides thereof. While the 65 spikes 28 may be turned down to tightly

clamp the fastening clips and tie plate in place on the tie, such tightness is apt to be gradually relieved, for the reason that the tie plate gradually becomes embedded in the tie. In order to maintain the clip tightly against 70 the tie plate and the latter tightly against the tie, spiral springs such as indicated at 31 may be interposed between the head of the spike and the top surface of the clip. A limited amount of looseness may be taken up by such spiral springs. It is contemplated, of course, that maintenance men should from time to time turn down the screw spikes so as to firmly and rigidly hold the clips and tie plates against the tie, and that the spring take-up arrangement should be effective to maintain the firm seating of the parts during the intervals between the servicing of the structure. Mechanical wear on the tie fibre is largely eliminated by thus maintaining the tie plate firmly seated on the tie. 80 85 90 95 100

It should be noted that because of the spaced arrangement of the overlying lip portions 25 of the rail-fastening clips relative to the base flange of the rail, the normal vertical movement of the rail will not tend to lift the clips nor to draw out the spikes. The overlying lip portions of the clips, the shoulder extension portions of the clips, and the tie plate with its rail-abutting shoulders as illustrated in Figure 1, constitute in effect a housing which embraces a portion of the rail base flange so that the rail is effectively located in proper position transversely of its length and limited with respect to its vertical movement. 105 110 115 120 125 130

It is desirable to provide tie plates with spike openings 29 adjacent each side at both ends, as shown in Figures 1 and 2, and in some instances it is desirable to provide an additional spike hole intermediate the holes 29 (as indicated in Fig. 3) to permit the fastening clips to be mounted in oppositely disposed positions centrally of the plate. In either arrangement, the tie plate 15 may be secured directly to the tie by means of spikes driven through selected spike holes 29 in addition to the spikes driven through other openings for also securing the clips in place, or independently of the means for securing the clip to the plate when the clip is secured thereto by welding only. 130

Referring now to Figures 4 and 5, I have illustrated a tie plate 32 mounted on a tie 33 for supporting a rail, the base portion of which is indicated at 34. The tie plate 32 includes a rail seat portion 35 having a rail-abutting shoulder 36 at one side thereof and end portions 37 and 38 projecting outwardly from the opposite sides of said rail seat portion. The bottom surface of the tie plate 32 in this instance includes depending projections which comprise primary tie-engaging ribs 39-39 and initial embedment portions 40-40. In some instances, the tie is pro-

vided with grooves extending transversely thereof for receiving the ribs 39—39 so that the tie plate is immediately anchored to the tie against relative movement longitudinally of the tie. The initial embedment portions 40—40 are quickly embedded in the tie to increase the interlock between the tie plate and the tie as an incident to the passage of a few trains over the tie plate, after which the tie plate, as a whole, begins to be embedded in the tie to a limited extent.

On the gauge side of the rail, i. e., the inside, a rail-fastening clip 41 is provided for anchoring the rail to the tie plate. This clip 15 includes a main body portion 42 and an upwardly offset lip portion 43 which extends over the adjacent flange portion of the rail in vertically spaced relation thereto. The clip 41 is also provided with a shoulder portion 44 which is adapted to engage the adjacent edge of the rail base flange to prevent lateral inward displacement of the rail. The body portion 42 of the clip is provided 25 with an opening 45 through which a spike may be driven, the tie plate being provided with a registering opening 46 and the top surface of the clip being countersunk, as indicated at 47, to receive the under side of the spike head. Such recessing or countersinking 30 of the clip body permits the spike to penetrate the tie to a greater extent than is possible where the spike is driven into the tie immediately adjacent the base flange with the head of the spike overlapping said base flange.

On the outside of the rail, I provide a fastening clip 48 which includes a main body portion 49 and a lip portion 50 which overlies the adjacent portion of the rail base flange in vertically spaced relation thereto. The body portion 49 of the clip and the end portion 38 of the tie plate are provided with registering openings, as indicated, to receive a spike 51 for fastening the clip to the tie plate and both parts to the tie. The top surface of the clip body portion is also recessed or countersunk to receive a portion of the spike head to permit increased penetration of the spike in the tie, as previously explained. The bottom surface of the clip 48 is shaped to conform to the top surface of the end portion 38 including the rail-abutting shoulder 36, and in providing the upwardly offset portion of the lip 50, a rail-abutting shoulder extension 52 may conveniently be provided. The shoulder extension 52 is preferably set back with respect to the rail-abutting shoulder 36, so that the side edge of the rail flange will not contact therewith, whereby abrasion of the clip is avoided, as explained above in connection with the structure illustrated in Figure 1.

The rear or outer ends of each of the clips 41 and 48 are provided with recesses for receiving the claws of a claw bar to facilitate

withdrawal of the spikes when desired. Such claw bar recesses are indicated at 53 in Figures 4 and 6 and are located at the rear corners of the clip, as most clearly indicated in Figure 6.

In both forms of construction above described, it will be noted that the spikes which penetrate the tie are removed from the edge of the rail base flange so that the spike holes in the tie plate are spaced outwardly from the zone of greatest stress and required strength in the tie plate. Hence, weakening of the tie plate is avoided by the described arrangement, and reduction of the weight of the plate by recessing as in Fig. 1 is permitted. Also, it will be noted that because of the greater distance between the spikes on opposite sides of the rail, the tie itself is not so apt to split as an incident to the driving of the spikes thereinto. Another advantage of this arrangement is found in the fact that it is somewhat easier to punch the spike holes in the relatively thin end portions of the plate than in the conventional manner, i. e., at the edge of the rail seat which is normally the thickest portion of the plate. Less injury is caused to the plate, and such injury as may necessarily result from the punching is removed from the zone of greatest stress.

The fastening clips above described are obviously much wider than the width of the spike, so that there is a greater area of clip surface disposed adjacent the rail base flange. Such greater clip area obviously has an increased rail-holding power and much greater resistance to wear as an incident to the movement of the rail which occurs under normal conditions. Hence, a distinct advantage in permanency is obtained in the use of the structure above described.

It has been found that under normal conditions the spikes are sometimes accidentally pulled out or broken off, with the result that there is considerable danger of rail spreading. To provide an increased factor of safety by preventing such possible rail displacement, one of the clips on each tie plate may be welded to the tie at the opposite sides of the tie clip, as indicated at 54 in Figure 2. In a length of track construction, as illustrated in Figure 9, it would be preferable to weld alternately disposed clips, as indicated, while securing the opposite or intermediate clips only with a spike. By this arrangement, all of the spikes, both from the welded clips and the spike-secured clips, may be drawn, in which event the welded-on clips would remain in place and afford considerable holding power to retain the track in proper position. Because of the interlocked relation between the tie plate and tie after the tie plate is embedded in the tie as above explained, the rail will be reasonably well held in place even though the spikes which nor-

10 mally hold the plates in place are drawn. Of course, a totally unspiked condition should not be permitted to remain, and the welded arrangement is intended more particularly as an additional safety factor. Of course, it may be found desirable under some conditions to weld all tie clips to the tie plates and to omit any spike securement of the clips, in which case the tie plate should be 15 secured to the tie, by spiking or otherwise, independently of the tie clip.

15 I am aware that changes and modifications in the above described structures may be made without departing from the spirit of my invention, the scope of which should therefore be determined by reference to the following claims, the same being construed as broadly as possible consistent with the state 20 of the art.

20 I claim as my invention:

25 1. In combination, a tie plate having a rail seat portion, end portions projecting from the opposite sides of said rail seat portion, and a rail-abutting shoulder at one side of said rail seat, a rail seated on said rail seat, and a fastening clip seated on the end portion of the tie plate outside of said rail-abutting shoulder and provided with a shoulder portion constituting an extension 30 of said tie plate shoulder, and a lip portion overlying the base flange of the rail in spaced relation thereto.

35 2. In combination, a tie plate having a rail seat portion, end portions projecting from the opposite sides of said rail seat portion, and a rail-abutting shoulder at one side of said rail seat, a rail seated on said rail seat, and a fastening clip seated on the end portion of the tie plate outside of said rail-abutting 40 shoulder and provided with a shoulder portion constituting an extension of said tie plate shoulder, and a lip portion overlying the base flange of the rail, the shoulder portion of the clip being set back relative to the rail-abutting shoulder of the tie plate to prevent abrasion of the clip shoulder incident to 45 vertical movement of the rail.

50 3. In combination, a tie plate having a rail seat portion and end portions projecting from the opposite sides of said rail seat portion, a rail-abutting shoulder on the tie plate at one side of said rail seat, a rail seated on said seat, fastening clips secured to said tie plate on its end portions and having lips projecting towards the rail and overlying the base flange of the rail in vertically spaced relation thereto, said tie plate, rail-abutting shoulder and fastening clips co-operating to 55 form a housing embracing a portion of the rail base to retain the same in predetermined position transversely of its length while permitting limited vertical movement of the rail.

60 4. In combination, a tie plate having a rail seat portion, end portions projecting from the opposite sides of said rail seat portion,

70 rail-abutting shoulders at the opposite sides of said rail seat, a rail seated on said seat between said shoulders, and fastening clips secured to said end portions, said clips having shoulder portions constituting vertical extensions of said tie plate shoulders, and lip portions projecting inwardly over the base flange of the rail in vertically spaced relation thereto, said rail seat, rail-abutting shoulders, clip shoulder extensions and lip portions constituting a housing embracing a portion of the rail base to retain the same in predetermined position transversely of its length while permitting limited vertical movement of the rail.

75 5. A clip for anchoring a rail to a tie comprising a main body portion and an upwardly offset lip portion projecting from one end of the body portion, reinforcing ribs at the sides of the clip projecting upwardly therefrom, extending along the side edges of the clip, across the angle between said body portion and offset lip, and merging into said lip below its top surface, the body portion of said clip being provided with an opening intermediate said ribs for receiving a spike.

80 6. A clip for anchoring a rail to a tie comprising a main body portion having an opening for receiving a spike for fastening the clip to a tie, and an upwardly offset lip portion projecting from one end of said body portion, the opposite end of the body portion having in its bottom surface a pair of spaced recesses opening to said opposite end for receiving the claws of a claw bar to facilitate 85 withdrawal of the spike from a tie through the agency of the clip.

85 7. In a rail mounting, the combination of a plurality of spaced ties, tie plates positioned on said ties, a rail extending transversely of the ties and seated on said tie plates, and a pair of clips secured to each of said tie plates, one on each side of the rail, for anchoring the rail to the tie plates, alternately disposed clips being permanently secured to the tie plate, and the clips disposed opposite to, or intermediate, such permanently secured clips being removably mounted, substantially as described.

90 8. In a rail mounting, the combination of a plurality of spaced ties, tie plates positioned on said ties, a rail extending transversely of the ties and seated on said tie plates, and a pair of clips secured to each of said tie plates, one on each side of the rail, for anchoring the rail to the tie plates, certain of the clips on one side of the rail being welded to their respective tie plates and certain other clips on the opposite side of the rail being welded to their respective tie plates, the clips disposed opposite to such welded-on clips being removably mounted, substantially as described.

95 9. In combination, a tie plate having a median portion and an end portion, an upwardly projecting shoulder on said tie plate

intermediate said median and end portions, a rail seated on said median portion with one edge of its base flange disposed adjacent said shoulder, a clip having a body portion seated on the end portion of said tie plate and having a lip portion projecting inwardly over the base flange of said rail, said clip having a shoulder normally spaced horizontally from the edge of said base flange and constituting an extension of said tie plate shoulder and said lip projecting inwardly from said shoulder over the adjacent portion of said flange in vertically spaced relation thereto, the body portion of said clip having an open-sided opening extending therethrough, a headed fastening device extending through said opening for uniting the clip to said tie plate, said open-sided opening permitting said clip to be inserted under, or removed from under, the head of said fastening device when the latter is nearly but not completely seated, by lateral movement of the clip relative to the fastening device.

10. In a rail support and fastening, the combination of a tie, a tie plate positioned on the tie, a rail seated on the tie plate, a clip having a body portion seated on the tie plate and a lip portion overlying the base flange of said rail, a spike extending through said clip and tie plate and into the tie for securing said parts to the tie, and welding between the side portions of said clip and tie plate for additionally and independently securing the clip to the plate.
